UNITED STATES PATENT OFFICE.

RICHARD E. KRAUSE, OF CLEVELAND, OHIO, ASSIGNOR TO THE KRAUSE CARBURETER COMPANY, OF CLEVELAND, OHIO, A CORPORATION OF OHIO.

CARBURETER FOR COMBUSTION-ENGINES

948,612.

Specification of Letters Patent.

Patented Feb. 8, 1910.

Application filed April 6, 1908. Serial No. 425,383.

To all whom it may concern:

Be it known that I, RICHARD E. KRAUSE, a subject of the King of Sweden, residing at Cleveland, in the county of Cuyahoga and State of Ohio, have invented certain new and useful Improvements in Carbureters for Combustion-Engines; and I hereby declare the following to be a full, clear, and exact description of the invention, such as will enable others skilled in the art to which it pertains to make and use the same.

This invention relates to improvements in what are known in the art as multiple-jet carbureters for combustion engines.

One object of this invention is to construct an exceedingly simple and reliable carbureter in which the air and gasolene or hydrocarbon of the combustible mixture to be fed to the engine are commingled in the proper proportion for attaining perfect combustion without any auxiliary compensating valves, and supplied to the engine in the required quantity and in the said proportion during any speed or load of the engine.

Another object is to construct a carbureter of the character indicated which comprises a valve controlling communication through a multitude of ducts to which air and gasolene or liquid fuel is supplied and which are arranged to discharge into a mixing chamber in common which has an outlet employed to feed the combustible mixture from the mixing chamber to the engine, which valve is arranged and movable to successively uncover the ducts covered thereby and has a limited play vertically so that the suction created within the mixing chamber during the operation of the engine will raise the said valve enough to permit the passage of some air and liquid fuel or mixture from all of the valve-covered ducts to the mixing chamber and thereby avoid any jerking of the engine during the actuation of the valve to successively uncover the said ducts.

Another object is not only to supply such a quantity of fuel to each duct relative to the supply of air to the said duct that the proportion of fuel and air supplied to each duct shall substantially correspond with the relative proportion of fuel and air supplied to any one or any number of the other ducts during the passage of fluid through the said ducts in the operation of the carbureter

so as to insure the proper mixture of gasolene or hydrocarbon and air for any speed or load of the engine in connection with which the carbureter is used, but to regulate or control the flow of fuel through all the fuel-feeding nozzles uniformly and simultaneously.

Another object is to provide a valve for regulating the supply of the combustible mixture from the mixing chamber through the outlet of the said chamber, and to have the said valve and the aforesaid valve employed in controlling the supply of air and liquid fuel to the mixing chamber operated simultaneously and so relatively arranged that the suction created within the mixing chamber is increased or decreased simultaneously with an increase or decrease in the supply of air and liquid fuel to the mixing chamber until the said valve for controlling the suction or partial vacuum within the mixing chamber is fully open so that the suction or partial vacuum created in the mixing chamber during the operation of the engine is properly governed.

Another object is to provide such a number of the said ducts and such an arrangement of the ducts and valve controlling the passage of fluid from the said ducts into the mixing chamber relative to the operation of the suction-governing valve that when the latter is fully open all of the said ducts shall not yet have been uncovered so that additional air and liquid fuel may be supplied to the mixing chamber as required for the maximum speed of the engine carrying a normal load and thereby enable the maintenance of a suitable vacuum in the mixing chamber when the engine is overloaded as is generally the case in automobiles going up hill.

Another object is to construct a carbureter of the character indicated in which the supply of liquid fuel to the fuel-discharging nozzles of the carbureter is controlled by a float within the liquid-fuel-holding chamber of the carbureter, and to provide means whereby the float-operated mechanism employed in opening the valve which controls the supply of liquid fuel to the said chamber is adjustable from the exterior of the carbureter to establish the required liquid-level within the said chamber while the engine is running.

With these objects in view, and to the end

of realizing any other advantages herein-after appearing, this invention consists in certain features of construction, and combinations of parts, hereinafter described, pointed out in the claims, and illustrated in the accompanying drawings.

In the said drawings, Figure 1 is a vertical central section of a carbureter embodying my invention. Fig. 2 is a horizontal section 10 on line 2—2, Fig. 1, looking downwardly. Fig. 3 is a horizontal section corresponding with Fig. 2, except that in Fig. 3 the valve employed in controlling communication through the outlet of the mixing chamber is 15 shown fully open, whereas in Fig. 2 the said valve is only shown slightly open. Portions are broken away in Fig. 3 to reduce the size of the figure. Figs. 4, 5 and 6 are horizontal sections on lines 4—4, 5—5, and 6—6, respectively, Fig. 1, looking downwardly.

My improved carbureter preferably comprises a cylindrical vertically arranged metal shell A which is provided internally and between its ends, but preferably a short distance below the upper end of the shell, with a partition *a* which is arranged horizontally or transversely of the shell and separates the space 10 and the chamber 12 which are formed respectively next above and next below the said partition within the upper end and lower portion respectively of the said shell. A float F is contained within the chamber 12. The float F is provided at its upper end with an upwardly projecting vertically arranged stem *f*. The float may be made of cork or in any other approved manner. The float-containing chamber 12 is closed at its lower end by a head B which is suitably attached to the lower end of the shell A. A short distance below the head B and in suitable proximity to the central portion of the head (see Fig. 1) is arranged an upright annular shell *b* which forms the surrounding wall of a chamber 16 arranged to receive gasoline or other liquid fuel supplied to the said chamber through a screen 17 which extends transversely of the lower end of the chamber and is held, against the under side of an annular flange 18 formed internally of the lower end of the said shell, by an upwardly projecting vertically arranged annular flange *d* formed upon a head D which overlaps and is suitably attached to the lower end of the shell *b* and forms the bottom of the chamber 20 which is arranged next below the screen 17 and whose surrounding wall is formed by the flange *d*.

C indicates the pipe for supplying gasoline or other liquid fuel to the carbureter 60 and extends through the head D and communicates at its discharging end with the chamber 20. The shell *b* is screw-threaded internally at its upper end and screwed onto the externally screw-threaded lower end of 65 an upright valve-casing E which is screw-

threaded externally at its upper end and screwed into a correspondingly threaded aperture extending vertically through the head B. The valve-casing E is provided internally with a passageway 27 which extends longitudinally of the valve-casing and is in communication through orifices 28 formed in the valve-casing with the chamber 16 and consequently in communication with the liquid-fuel-supply pipe C. The passageway 27 connects at the upper end of the valve-casing E with and forms the fuel-inlet of the float-containing chamber 12.

A valve K is arranged within the passageway 27 and adapted to control communication through the said passageway. The valve K is conical and movable vertically within the passageway 27 and in its upper and closed position engages a valve-seat 30 with which the valve-casing E is provided internally. The valve K is provided with a depending stem 32 which extends downwardly into and has lateral bearing within an externally screw-threaded bushing 33 which is screwed into the lower end of the valve-casing. A spiral spring *k* is mounted and confined on the valve-stem 32 between the valve-proper and the bushing 33 and acts to retain the valve K in its closed position. The valve K is provided centrally with a vertically upwardly projecting stem 35 which is arranged centrally of and extends through the upper end of the passageway 27 and a suitable distance upwardly into the float-containing chamber. The valve-stem 35 has its upper end engaging the under side of a lever M. The lever M is provided at one side and a suitable distance from the valve-stem 35 with an upwardly projecting lug or member *m* which engages the under side of the float F, and the said lever (see Figs. 1 and 6) is horizontally pivoted or fulcrumed, as at *h*, at the opposite side of the said valve-stem to a bracket L which is forked, at its outer end, as at *l*, to accommodate the engagement of the said bracket with an annular recess 34 which is formed in and extends circumferentially of the upper end-portion of a vertically arranged screw I which is arranged between the fulcrum of the lever and the outer extremity of the forked end-portion of the bracket and nearer the last-mentioned extremity than to the said fulcrum. The screw I engages and extends through a correspondingly arranged and correspondingly screw-threaded hole 26 formed in the head B, and a nut J is mounted on the said screw at the under side of the said head and secures the screw in the desired adjustment. It will be observed that the forked end *l* of the lever-bearing bracket L loosely fits the recess 34 and that the said bracket is supported from the screw without interfering with the turning of the screw independently of the 130

bracket. To positively prevent turning of the bracket L with the screw during any turning and consequent readjustment of the screw the head B is provided between the screw and the fulcrum h of the lever M with an upwardly projecting pin or member 24 which engages a hole 25 formed in the said bracket.

In Fig. 1 of the drawings 15 indicates the liquid-level required to be maintained within the float-containing chamber, and the arrangement of the parts is such that the valve K is closed by the spring k when the said liquid-level obtains within the said chamber. Obviously however as soon as the said liquid-level falls the float F lowers by gravity and thereby actuates the lever M in the direction required to effect the depression of the valve-stem 35 so as to open the valve K against the action of the spring k and permit additional liquid fuel to pass into the float-containing chamber at the fuel-inlet of the said chamber until the required liquid-level in the said chamber is reestablished. It will be observed also that the lever M constitutes float-operated means employed in opening the valve K which controls the supply of liquid fuel to the float-containing chamber through the fuel-inlet of the said chamber, and that the fulcrumed end of the said lever M, being supported from the vertically adjustable screw I through the medium of the bracket L, is adjustable vertically from the exterior of the carburetor. Obviously to effect the establishment of the required liquid-level within the float-containing chamber preparatory to the operation of the carburetor, it is only necessary to loosen the nut J and thereupon manipulate the screw I to properly adjust the lever-bearing bracket L vertically, and the said bracket is secured in the desired vertical adjustment by tightening the nut. Obviously therefore in my improved carburetor the liquid-level within the float-containing chamber is adjustable from the exterior of the carburetor during the running of the engine.

An inverted cup-shaped member P is arranged above and centrally of the space 10 and provided at its lower end and externally with an annular flange p which rests upon and is suitably secured to the upper end of the shell A. The member P forms an upward extension of the space 10, and the space 10 and its upward extension or enlargement by the said member P forms a mixing chamber in which air and gasoline or other liquid fuel commingle to form the combustible mixture which is to be supplied to the cylinder 60 of the engine in connection with which my improved carburetor is to be used.

A tubular or hollow shaft R is arranged centrally of the mixing chamber and extends vertically upwardly from the lower end of the said chamber through the chamber and

a suitable distance above the chamber. The shaft R is operatively provided at its lower end with a flat rotary valve r which is seated on the bottom of the mixing chamber, which bottom is formed by the partition a.

The shell A is considerably increased in thickness at one side of the float-containing chamber 12 to accommodate the formation in the said thicker portion of the surrounding wall of the float-containing chamber of a multitude of upright ducts 50 which are arranged therefore at one side and externally of the said chamber and spaced circumferentially of the said chamber and equidistantly from the shaft R. Each duct 50 extends downwardly from the bottom of the mixing chamber and at its lower end is provided with a lateral air-inlet 49 which is continually in communication with the external atmosphere. The bottom of each duct 50 is provided with a screw-threaded hole 52 which extends vertically through the said bottom, and a corresponding externally screw-threaded nozzle Q is screwed into the said bottom at the said hole and projects vertically upwardly into the said duct and discharges at its upper end into the duct preferably at a point opposite the central portion of the inner end of another lateral air-let 48 with which the said duct is provided at its outer side and above the air-inlet 49 of the duct. Each nozzle therefore establishes communication between the duct into which it discharges and the float-containing chamber. Each nozzle (see Fig. 1) preferably has a cup-shaped upper end 46 which is provided in its bottom and centrally with an upwardly discharging orifice 47 which is the outlet of the passageway 45 formed in the nozzle and communicating at the lower end of the nozzle with the float-containing chamber, and preferably the relative arrangement of the parts is such that the cup-shaped upper end of each nozzle has its upper extremity above the liquid-level required to be maintained in the float-containing chamber and has its bottom below the said liquid-level so that during the operation of the carburetor a small quantity of liquid fuel is always present in the cup-shaped upper end of the nozzle.

The shell A is provided at the outer ends of the upper air-inlets 48 of the ducts (see Figs. 1 and 5) with an annular recess 42 which extends circumferentially of the shell 120 and is engaged by a valve-forming ring 43 which is seated on the bottom of the said recess and is shiftable circumferentially of the said shell. The ring or valve 43 is provided with as many lateral ports 44 as there are ducts 50, which ports are continually in communication with the external atmosphere, and the relative arrangement of the parts is such that when the said valve is open its ports 44 register with the air-inlets 125 130 135

48 of the said ducts, and imperforate portions of the valve cover the said air-inlets 48 when the valve is closed. It will be observed therefore that my improved carbureter is provided with a valve for simultaneously regulating or controlling the supply of air to all of the ducts 50 at the upper air-inlets 48 of the said ducts. The ducts 50 correspond in dimensions and fluid-conducting capacity. The lower air-inlets 49 of the ducts correspond in dimensions and air-supplying capacity. The upper air-inlets 48 of the ducts correspond in dimensions and air-conducting capacity. The ports 44 in the valve correspond in dimensions and air-supplying capacity. Obviously therefore the supply of air to all the air-ducts 50 in my improved carbureter is uniform, and the supply of air to the upper air-inlets of the said ducts is uniformly regulated, thereby governing the supply of fuel through the nozzles for the purpose of maintaining a suitable vacuum around the discharging ends of the nozzles during the operation of the carbureter. The valve-forming ring 43 (see Fig. 5) is preferably made in halves or sections suitably secured together by screws 36 which engage correspondingly threaded holes formed in lugs 37 with which adjacent ends of the said sections are provided. The arrangement of the parts and the dimensions of the valve *r*, as illustrated, are such that the said valve is adapted to cover all save one of the ducts 50 in the fully closed position of the valve. The valve *r* uncovers the valve-covered ducts successively in actuating the valve from its fully closed into its fully open position. The valve *r* therefore controls communication with the mixing chamber through a multitude of ducts 50.

The valve-operating shaft *R* has lateral bearing within a box 53 depending from the top wall of the mixing chamber. The shaft *R* is provided at the lower end of the box 53 with a collar 54 which co-operates with the said end of the box in limiting the upward movement of the shaft, but the collar 54, when the valve *r* is in position resting upon the bottom *a* of the mixing chamber, is spaced somewhat from the lower end of the said box, as at *s*, to afford a limited play vertically to the valve *r*. The collar 54 is preferably secured to the shaft *R* by a set-screw *u* to render the collar adjustable endwise of the shaft and thereby permit an accurate spacing of the collar relative to the lower end of the box 53 and also to render the collar and connected valve adjustable circumferentially of the shaft into the desired position relative to the outlet *o* of the mixing chamber. The valve *r* seats by gravity in the absence of enough suction or partial vacuum in the mixing chamber to lift the valve from its seat, but the limited

play vertically afforded to the valve as hereinbefore described permits the raising of the valve by the requisite suction created within the mixing chamber, and the great importance of this vertical play of the valve 70 is evident because it enables the suction created within the mixing chamber during the operation of the engine to raise the valve enough to permit the passage of some air and liquid fuel or mixture from all of the 75 valve-covered ducts to the mixing chamber and thereby effectually avoid any jerking of the engine during the actuation of the valve to successively uncover the said ducts. Preferably a bushing 55 is arranged within 80 the valve-operating shaft *R* and loosely surrounds the float-stem *f*, which bushing is externally screw-threaded at its lower end and screwed into the partition *a*.

The shaft *R* is operatively provided at 85 its upper end externally of the mixing chamber with a spur-gear *t*, and a diametrically larger spur-gear *T* meshes with the gear *t* and is suitably supported from a lug 57 with which the inverted cup-shaped member *P* is externally provided. The gear *T* is provided with a lever 56 for turning the same.

The outlet *o* of the mixing chamber is shown formed at one side of the transversely smaller upper portion of the said chamber opposite the collar 54 which is provided with a valve-forming segment 58 which is arranged concentrically of the shaft *R* and has the arrangement and dimensions 95 required to interrupt communication through the outlet of the mixing chamber. In Fig. 2 the valve 58 is shown slightly open, and the arrangement of the parts is preferably such that when the valve 58 is slightly open as 100 illustrated in Fig. 2 the valve *r* is in its fully closed position in which the said valve *r*, as already indicated, covers all but one of the ducts 50. The relative arrangement of the parts is preferably furthermore such 110 that in the fully open position of the valve 58, as shown in Fig. 3, the valve *r* has uncovered all but one and a half of the ducts adapted to be covered thereby at one time so that when the valve 58 is fully opened 115 all the ducts 50 shall not yet have been uncovered so that additional air and liquid fuel may be supplied to the mixing chamber as required for the maximum speed of the engine carrying a normal load and thereby 120 maintain a suitable vacuum in the mixing chamber when the engine is overloaded as is generally the case in automobiles going up hill. The valve 58 regulates the supply of combustible mixture from the mixing 125 chamber through the outlet of the said chamber, and the said valve and the valve *r* employed in controlling the supply of air and liquid fuel to the mixing chamber are operated simultaneously and so relatively 130

arranged that the suction created within the mixing chamber is increased or decreased simultaneously with an increase or decrease in the supply of air and liquid fuel to the mixing chamber until the said valve for controlling the suction or partial vacuum within the mixing chamber is fully open so that the suction or partial vacuum created within the mixing chamber during the operation of the engine is properly governed.

By the construction and relative arrangement of parts hereinbefore described it will be observed that my improved carbureter comprises a float-containing chamber from which a multitude of nozzles supply the fuel to air-receiving ducts arranged outside of the said chamber and corresponding in number with the nozzles, which ducts respectively communicate at one end with the external atmosphere and the other end connect separately with a mixing chamber in common, which chamber has an outlet controlled by an adjustable valve simultaneously with the control by a valve of the discharge from the said ducts into the mixing chamber for the purpose of maintaining a suitable vacuum in the mixing chamber.

What I claim is:—

1. In a carbureter for a combustion engine, a mixing chamber having an outlet for feeding a combustible mixture to the engine; several air-receiving ducts connecting and adapted to communicate with the said chamber, which ducts are provided with air-inlets continually communicating with the external atmosphere and have other air-inlets; means whereby the supply of air to the ducts through the last-mentioned air-inlets is controlled or regulated; a suitably operated valve covering the discharging ends of at least a plurality of the said ducts in its fully closed position and arranged to successively uncover the valve-covered ducts in actuating the valve from its fully closed into its fully open position, and means for supplying fluid fuel to the ducts.

2. In a carbureter for a combustion engine, a mixing chamber having an outlet for feeding a combustible mixture to the engine; several air-receiving ducts connecting and adapted to communicate with the said chamber, which ducts are each provided with an air-inlet continually communicating with the external atmosphere and have another valve-controlled air-inlet; a valve for controlling or regulating the supply of air to each duct through the second-mentioned air-inlet of the said duct; a suitably operated valve covering the discharging ends of at least a plurality of the said ducts in its fully

closed position and arranged to successively uncover the valve-covered ducts in actuating the valve from its fully closed into its fully open position, and means for supplying the fluid fuel to the ducts.

3. In a carbureter for a combustion engine, a liquid-fuel-receiving chamber provided with a fuel-inlet suitably controlled; a mixing chamber arranged above and externally of the float-containing chamber and provided with an outlet for feeding a combustible mixture to the engine; upright ducts formed externally and spaced circumferentially of the float-containing chamber, which ducts connect and are adapted to communicate with the mixing chamber and provided with two vertically spaced lateral air-inlets the lower of which is continually in communication with the external atmosphere; means whereby the supply of air to the ducts through the upper air-inlets of all of the ducts may be regulated and liquid-fuel-conducting nozzles communicating with the first-mentioned chamber and discharging into the ducts opposite the upper air-inlets of the ducts.

4. In a carbureter for a combustion engine, a liquid-fuel-receiving chamber provided with a suitably controlled fuel-inlet; a mixing chamber arranged above and externally of the float-containing chamber, said mixing chamber being provided with an outlet for feeding a combustible mixture to the engine; upright ducts formed externally and spaced circumferentially of the float-containing chamber, which ducts connect and are adapted to communicate with the mixing chamber at the bottom of the mixing chamber, said ducts being provided with two vertically spaced lateral air-inlets the lower of which is continually in communication with the external atmosphere; a valve-forming member arranged externally and extending circumferentially of the float-containing chamber and arranged to regulate the supply of air to all of the ducts simultaneously through the upper air-inlets of the ducts; liquid-fuel-conducting nozzles arranged centrally of the lower portions of the ducts and communicating at their lower ends with the first-mentioned chamber, which nozzles discharge upwardly into the ducts opposite the upper air-inlets of the ducts.

In testimony whereof, I sign the foregoing specification, in the presence of two witnesses.

RICHARD E. KRAUSE.
